UNITED STATES PATENT OFFICE.

GEORGE W. ROBBINS, OF LAUREL, MINNESOTA.

RAIL-JOINT.

977,045.

Specification of Letters Patent. Patented Nov. 29, 1910.

Application filed February 10, 1910. Serial No. 543,088.

To all whom it may concern:

Be it known that I, GEORGE W. ROBBINS, a citizen of the United States, residing at Laurel, in the county of Koochiching, State 5 of Minnesota, have invented certain new and useful Improvements in Rail-Joints; and I do hereby declare the following to be a full, clear, and exact description of the invention, such as will enable others skilled in the 10 art to which it appertains to make and use the same.

This invention relates to rail joints, of that general class commonly known as scarf joints, and has for an object to so construct 15 the rail ends that their interfitting or engaging portions will be simpler in construction than heretofore.

Another object of the invention is to provide the end of a rail with engaging portions 20 that may be formed by a suitable die before the heated rail in the process of manufacture has become cooled.

A still further object is to provide a scarf joint the members of which will have their 25 interlocking means reinforced in a more positive manner than usual.

To attain the above ends my invention 30 consists of certain novel details of construction and combination of parts which will be hereinafter more fully described and claimed.

In the accompanying drawings forming part of this specification, Figure 1 is a perspective view of a railway joint formed in 35 accordance with my invention. Fig. 2 is a detail perspective view of one of the joint members. Fig. 3 is a detail perspective view of the other member of the joint. Fig. 4 is a transverse sectional view through the 40 joint.

Referring now to the drawing in which like characters of reference designate similar parts in the views shown 5 and 6 designate the meeting ends of two adjacent rails. 45 The extreme end of one rail is mutilated as shown, one side of its head, web, and flange being cut away to approximately the middle vertical diameter of the rail to provide a lateral rabbet 7 equal in size to approximately one-half the cross dimension of the parts. The projecting portion 8 of each rail formed by this mutilation of the rail end projects into the lateral recess 7 of the

mating rail end, the extreme end face 9 of said projecting portion being disposed in 55 abutting contact with the end face 10 of said rabbet.

A locking lug 11 projects forwardly from the end face of each projection 8 and engages in a recess 12 formed in the end face 60 10 of the rabbet formed in the mating rail end, this locking lug preventing the vertical displacement of either of the rail ends and thereby obviating the liability of a low joint. 65

It is evident that the mutilation of the opposite ends of a rail may be formed by a single die, care being taken to so reverse the rail during the operation so that the rabbets at each end of the rail will be on opposite 70 sides thereof, and that the mutilation of each rail end is of such a simple character that the rail while still hot may be advanced into the die and formed with the above described mutilated end before it has become 75 cooled, and therefore the machining and finishing of such common necessity in the formation of scarf joints as hitherto constructed, entirely obviated.

A pair of fish plates 13 are bolted as 80 shown at 14 to the rail webs and are sufficient in length to extend considerably beyond the interfitting portions of the rail ends so that a tight connection between the parts may be maintained at all times. 85

In addition to the above locking means between the abutting rail ends the base flange of one of the rails is cut away on its bottom face to provide a rabbet 15 which engages a forwardly projecting extension 16 disposed 90 on the end face of the rabbet of the opposite rail flange. These interfitting portions of the rail base flanges serve to reinforce the interlocking means between the rail ends and as the bottom edges of the fish plates 95 bear against the top surfaces of the interfitting flanges a vertical displacement of the rail ends is prevented by the fish plates should the said interlocking means become broken. 100

From the foregoing description taken in connection with the accompanying drawing it is thought that the construction and operation of my invention may be easily understood without any more extended explanation, it being understood that various 105

changes in the form and proportion may be made within the scope of the appended claim.

What is claimed is:—

- 5 In a rail joint, interfitting rail ends each having a side portion of its head and web removed, one of said rail ends having a side portion of its base flange removed, the remaining side portion of said rail base flange having its under side cut away horizontally, and the other of said rail ends having the upper side of the corresponding half of its base flange cut away horizontally,
- 10

said mutilated portions bearing one upon the other, a locking lug projecting forwardly from the remaining side portion of each rail web, and a locking recess formed in the mutilated side portion of each rail web engaging said locking lug.

In testimony whereof, I affix my signature, in presence of two witnesses.

GEORGE W. ROBBINS.

Witnesses:

GENEVIEVE P. LAIDLLOW,
Mrs. E. C. PAQUIN.
